US00D324379S

United States Patent [19]
Izaki

[11] **Patent Number:** Des. 324,379
[45] **Date of Patent:** ** Mar. 3, 1992

[54] **ELECTRONIC COMPUTER**[75] Inventor: **Kenzo Izaki**, Chiba, Japan[73] Assignee: **Kabushiki Kaisha Toshiba**,
Kanagawa, Japan[**] Term: **14 Years**[21] Appl. No.: **446,710**[22] Filed: **Dec. 6, 1989**[30] **Foreign Application Priority Data**

Jun. 6, 1989 [JP] Japan 1-20668

CLAIM

The ornamental design for an electronic computer, as shown and described.

DESCRIPTION

FIG. 1 is a top, front and left side perspective view of an electronic computer showing my new design;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof;

FIG. 7 is a bottom plan view thereof;

FIG. 8 is a top, front and right side perspective view thereof showing the display panel and keyboard in closed position.

FIG. 1

FIG. 2
